INVENTOR.
JOHN K. WEISKOPF.

BY

B. J. Craig
ATTORNEY.

UNITED STATES PATENT OFFICE

JOHN K. WEISKOFF, OF ARCADIA, CALIFORNIA

GOLF CLUB

Application filed June 1, 1931. Serial No. 541,251.

This invention relates to golf clubs.

The general object of this invention is to provide an improved golf club including a head member having novel means therein for more effective striking a golf ball.

A further object of the invention is to provide a golf club including a hollow metal head having a novel striking face secured thereto.

10 An additional object of the invention is to provide a golf club including a head having a recess therein and having resilient striking surfaces fitted in said recess and secured thereto.

15 A further object of the invention is to provide a golf club including a head and a shaft wherein novel means is provided for securing the head to the shaft.

20 A further object of the invention is to provide an improved metal head for a golf club.

25 Other objects of the invention will be apparent from the following description taken in connection with the accompanying drawing, wherein:

Fig. 1 is a top plan view partly broken away, of a golf club showing the features of my invention.

30 Fig. 2 is a section taken on line 2—2, Fig. 1.

Fig. 3 is a section taken on line 3—3, Fig. 1.

Fig. 4 is a section taken on line 4—4, Fig. 1.

Fig. 5 is a top plan view of the resilient insert.

Fig. 6 is a front elevation of a golf club embodying my invention with a steel shaft shown as secured thereto, and,

Fig. 7 is a top plan view of the golf club on a reduced scale showing the method of assembling.

45 Referring to the drawing by reference characters, I have indicated a golf club em-

bodying the features of my invention generally at 10.

As shown this golf club includes a head 11 having a hosel 12 thereon. The head 11 comprises a lower portion 13 which is relatively thick and a top portion 14 which is relatively thin, and the head further includes a rear portion 15 and a front portion 16.

As shown the head is made for serving as 55 a driver or as a brassie, altho it will be understood that it may be designed and used as a putter or for other purposes.

The head is preferably cast of one piece of material which may be of suitable light 60 weight metal, such as aluminum alloy, and in casting the head, I preferably provide a web 17 which is connected to the back 15, the front 16, and the bottom 13, and the top 14 as indicated in the drawing. A second web 18 is likewise shown and this web is connected to the back and front of the club and to the top and bottom similar to the web 17. The two webs serve to take up the strain due to the impact of the club against 70 the ball and the webs are provided with prongs 19 which are directed towards each other and which include inclined forward faces 20 and rearwardly directed toward 21. The front of the club is removed to provide 75 an aperture 22 which receives a resilient insert 23. This insert may be made of a good grade of rubber vulcanized to the desired hardness, or it may be made of other 80 suitable material if desired.

The insert includes a striking portion 24 which is grooved as at 25. The striking portion is shaped to fit tightly against the inner wall of the head and is provided with a 85 rear portion 26 which has notches 27 therein corresponding to the prongs 19 previously described.

When the cushion member 23 is made, a nut 28 is embedded therein and an aperture 90

29 is provided which leads to and beyond the nut.

In assembling the club the resilient member is placed in position as shown in Fig. 7 5 and the ends are then forced into their place and the portion 26 is moved rearwardly until the prongs 19 engage the grooves 27.

A threaded fastening member 30 having a head 31 is then inserted through an aperture in the rear of the club head until it engages the bolt 28. The threaded member 30 is then tightened and the striking member is thus firmly secured in place.

My improved club head may be used either 15 with wood or metal shafts and as shown in Figs. 1 and 2 it is provided with a wooden shaft 34 which is fitted within an adapter 35. The shaft may be secured to the adapter by means of a screw 37 or in other desired 20 manner. The adapter includes a hollow portion in which the end of the shaft 34 is secured and an intermediate portion 38 which terminates in a solid portion 39, which is slightly tapered towards its end and which 25 fits in a slightly tapered socket 40 in the hosel 12.

A screw 41 may serve to hold the adapter in the socket 40.

In Fig. 6 I have shown my improved club 30 as including a steel shaft 45 which has a lower end 46 slightly tapered and fitted in the socket 40 in the hosel 12. A screw 48 may serve to hold the shaft 45 in the socket 40.

35 From the foregoing description, it will be apparent that I have invented an improved golf club which is highly efficient and is effective to prevent slicing and pulling to a marked degree and which attains 40 its efficiency even when the play is with a ball which is wet.

Having thus described my invention, I claim:

45 1. In a golf club, a head having a handle secured thereto, said head comprising a bottom portion and a top portion, said bottom and said top portions being connected by a side wall, the front of said head being open and having a resilient insert secured therein, 50 a pair of ribs connecting said top and bottom portions and spaced from the side walls thereof, said insert having a portion extending between said ribs and means to secure the entire resilient insert in place.

55 2. In a golf club, a head having a handle secured thereto, said head comprising a relatively thick bottom portion and a relatively thin top portion, said bottom and said top portions being connected by a side wall, the 60 front of said head being open and having a resilient insert secured therein, a pair of ribs connecting said top and bottom portions and spaced from the side walls thereof, said ribs having teeth thereon, said insert having a portion extending between 65

said ribs and engaging said teeth and means to secure said resilient insert in place.

3. In a golf club, a head having a front portion and having handle secured thereto, 70 said head comprising a bottom portion and a top portion, said bottom and said top portions being connected by a web spaced from the front of said head and parallel to said front, the front of said head being open and having a resilient insert secured therein, 75 said insert engaging said web.

In testimony whereof, I hereunto affix my signature.

JOHN K. WEISKOPF.
